UNITED STATES PATENT OFFICE.

MASSEY SITNEY, OF BROOKLYN, NEW YORK.

HAND BAG.

Application filed September 19, 1921. Serial No. 501,776.

To all whom it may concern:

Be it known that I, MASSEY SITNEY, a citizen of the United States, and a resident of Brooklyn, Kings County, and State of New York, have invented certain new and useful Improvements in Hand Bags, of which the following is a specification.

This invention relates to hand bags.

At the present time most of the hand bags in general use are provided with a single receptacle into which such articles as car tickets, chains, mirrors, powder puffs, etc., are thrown indiscriminately so that confusion is attended with the locating of any of these articles causing annoyance to the user of the bag.

One of the objects of the invention is to overcome the difficulties above set forth and to provide a hand bag with a plurality of pockets so constructed and arranged that access may be had to one of the pockets without necessitating the opening of another of the pockets.

Another object of the invention is to provide a hand bag having a plurality of pockets with a simple frame construction in which the same frame member is utilized for a plurality of pockets thereby providing a construction having a minimum of parts.

Another object of the invention is to provide a hand bag with an auxiliary pocket so constructed and so connected with the bag that the auxiliary pocket will not detract from the appearance of the bag and may be opened without opening the bag.

Further objects of the invention will appear from the following specification taken in connection with the drawings which form a part of this application, and in which—

Fig. 1 is a perspective view of a hand bag constructed in accordance with my invention.

Fig. 2 is a sectional elevation on an enlarged scale of the construction shown in Fig. 1, and

Fig. 3 is a perspective view, partly broken away, showing the construction illustrated in Fig. 1, but with the closure for the auxiliary pocket open.

The invention may be briefly described as comprising a hand bag having a plurality of main frame members pivoted together and having secured thereto a body of the bag, one or both of the main frame members having one or more extensions rigidly carried thereby and preferably formed integral

therewith. An auxiliary pocket is secured to this rigid frame extension and a closure for this pocket is pivoted to this extension. A separate and independent clasp is provided for the main frame members and for the pocket closure.

Referring to the drawings, I have shown a hand bag having a main body 10 formed of fabric or any other suitable material, the body 10 being secured to a pair of frame members 11 and 12 pivoted on each other at 13. In the form of the invention shown, the frame members are formed with parallel edge portions 14 between which the body 10 is secured. Each of these members has secured to the upper face thereof a clasp member 15, the members 15 cooperating in a well known manner to fasten the members 11 and 12 of the bag in closed position. A handle 16 of any suitable construction is secured to the members 11 and 12 as shown in Fig. 1.

The main frame member 11 has rigidly secured thereto or formed integral therewith an auxiliary frame member or extension 17, this frame member extending downwardly from the main or longitudinally extending portion 18 of the frame member 11 and forming with the portion 18 of the member 11 a closed rectangle. It will be understood, however, that any other shape of frame 17 may be used if desired.

The body 10 of the bag is secured in the channel formed by the parallel edges 20 of the extension and extends around the auxiliary frame 17.

A rectangle closure frame 21 is pivoted on pivot pins 21' to the frame member 17 and the closure frame is preferably U-shaped in section. A pocket 22 is secured to the frame 21 in the channel between the parallel flanges of the U-shaped section and is also secured to an inwardly extending flange 23 formed on the frame member 11, as shown in Fig. 2. A cover 24, preferably of fabric, is also secured in the channel of the frame 21 thereby closing the opening of the pocket.

A latch 25 is pivoted at 26 to the closure frame 21 and is adapted to engage a downwardly extending lug 27 carried by the flange 23. A spring 28 retains the latch in engagement with the lug 27. A handle 29 is carried by the latch.

The closure frame 21 and the frame extension 17 are connected by gussets 30 which are adapted to fold inwardly when the frame 21 is swung to closed position.

From the showing in Figs. 1 and 2, it will be noted that the auxiliary pocket 22 is disposed within the main body 10 of the bag and does not detract in any way from the 5 appearance of the bag. The lower part of this pocket extends below the lower edge of the closure frame as at 22^A thus forming a safety compartment with its edges sewed together as at 22^B. Furthermore, it will 10 be noted that separate and independent latches are secured for the frame members 11 and 12 and for the pocket and that the bag may be opened without opening the pocket or the pocket may be opened without 15 opening the bag.

Although one specific embodiment of the invention has been illustrated and described, it will be understood that the invention is capable of modification and that changes in 20 the construction and in the arrangement of the various cooperating parts may be made without departing from the spirit or the scope of the invention as expressed in the following claims.

25 What I claim is:

1. A bag comprising a frame having an auxiliary frame rigidly connected therewith, a closure frame member pivoted to the auxiliary frame and adapted to swing 30 outwardly relative thereto and flexible means connecting the pivoted frame member to the auxiliary frame.

2. In a bag, a main frame member having an auxiliary frame rigidly carried 35 thereby, a closure frame pivoted to the

auxiliary frame and a pocket body secured to the main frame member and to said closure frame.

3. In a bag, a pair of pivoted main frame members, a bag body secured thereto, an auxiliary frame formed rigid with one of the frame members, a closure frame pivoted to the auxiliary frame and a pocket body secured to the closure frame and to the main frame member in which the auxiliary frame is formed and extending into the bag body. 45

4. In a bag, a pair of pivoted main frame members, a bag body secured thereto, an auxiliary frame formed rigid with one of the frame members, a closure frame pivoted to the auxiliary frame, a pocket body secured to the closure frame and to the main frame member in which the auxiliary frame is formed and extending into the bag body, and separate clasps for the closure and for 50 the main frame members.

5. In a bag, a pair of pivoted main frame members, a bag body secured thereto, an auxiliary frame formed rigid with one of the frame members, a closure frame pivoted to the auxiliary frame, a pocket body secured to the closure frame and to the main frame in which the auxiliary frame is formed and extending into the bag body and below the lower edge of the auxiliary frame, and separate clasps for the closure and for 55 the main frame members. 65

In witness whereof, I have hereunto set my hand this 17th day of September, 1921.

MASSEY SITNEY.
